ATTORNEY

UNITED STATES PATENT OFFICE.

ANTHONY L. ASTE, OF BROOKLYN, NEW YORK.

SHOE-CLEANING-STICK CONTAINER, APPLICATOR, AND DISTRIBUTOR.

Application filed March 21, 1924. Serial No. 709,763.

To all whom it may concern:

Be it known that I, ANTHONY L. ASTE, a citizen of the United States, and a resident of the borough of Brooklyn, county of Kings, city and State of New York, have invented certain new and useful Improvements in Shoe-Cleaning-Stick Containers, Applicators, and Distributors, of which the following is a specification.

This invention relates to shoe cleaning stick container, applicator and distributor, which usually consists of having the material which is used to apply to the shoe, as for instance, to buck, or canvas, or suede shoes, or nappy leather shoes, arranged in compacted form, in the form of a cylindrical stick. Heretofore such compacted material in the form of sticks has been sold either as wrapped in paper or paper envelopes, in which case the user in removing the envelope and in utilizing the stick has the hands soiled in such use, or such sticks have been put into tin containers to enable the sticks to be readily grasped by the hand of the user without soiling the fingers. The object of this invention is to provide a new and improved container for such sticks, so as to enable the user to readily apply the stick to the shoe, and apply to the shoe the felt buffer or rubber in order to equally distribute the material of which the stick is made on the shoe.

For this purpose my invention consists of an improved shoe cleaning stick container, applicator and distributor, which in general is arranged to securely hold the stick and permit its adjustable forward movement in conformity with the amount of the compact used and also to provide means therein for holding the felt pad buffer or rubber in closed or unused position, and also permit it to be readily applied so as to enable the felt pad buffer or rubber to be held in position when it is desired to use the container for the stick as a holder for the felt pad buffer or rubber when applying the felt pad buffer or rubber to the shoe. The invention consists of certain further features, which will be fully described, hereinafter shown in the drawings and finally pointed out in the claims.

In the accompanying drawings:

Figure 1 shows a perspective view of a shoe adapted to be cleaned and shows the stick with its container being used to dis-

tribute by means of the felt pad buffer or rubber the cleaning material on the shoe.

Figure 2 shows a perspective view of the container with its compact in stick form protruding therefrom and the felt pad distributor shown in proximity to the compact to enable the user to take off from the compact certain material and apply it by means of the felt pad buffer or rubber to the shoe.

Figure 3 is a central section of the container and compact stick and felt pad distributor, all held within the container, the same being ready for shipment.

Figure 4 is a horizontal section taken on line 4-4 of Figure 3.

Figure 5 is a central section, showing the compact stick protruding and also showing the felt pad distributor held in position to enable it to be applied to the shoe, as shown in Figure 1.

Figure 6 is a central section showing a different position of the compact.

Figure 7 is a section taken on line 7-7 of Figure 6 and Figure 8 is a horizontal section taken on line 8-8 of Figure 6.

Similar characters of reference indicate corresponding parts throughout the various views.

Referring to the drawings and more particularly to Figures 1 and 5. The container 10 is of cylindrical shape, though it may be of any other suitable configuration. The container at one end thereof has a bent-over beveled portion 11, which provides a surrounded portion so that no ragged edges of the container appear. The container is preferably made of sheet tin or other similar suitable metal which lends itself readily to manufacturing ends. The other end of the container 10 has inwardly extending flanges 12 which surround an opening 13, as shown in Figure 6. The end of the container 10, near the bevel portion 11, is provided with a globular impression 14, which extends within the interior of the container 10.

Within the container 10, as shown in Figure 5, a metallic cap 15 having flanges 16, surrounds the stick 17 of compacted material, which has an exterior shape in substantial conformity with the interior shape of the container 10. This metallic cap 15 is arranged to act as a guide for the stick and its diameter is substantial to the diameter of the interior of the container 10.

This cap 15 is provided at one side thereof with a vertical depression 30 to enable the cap when inserted into the container 10, to pass that part of the container 10, where 5 the globular impression 14 enters therein. The compact stick 17 is provided at one side thereof with a longitudinal recess extending along the entire compact stick, this recess being indicated by 18. The depth of this 10 recess 18 is of such character as to permit the entrance therein of the impression 14, whereby the impression 14 acts as a guiding member to enable the compact stick 18 to slide to and fro in the container 10. The 15 entrance of the impression 14 into the recess 18 prevents the compact stick 17 from a rotary movement while the same is being moved in either direction in the container 10 and while the same is being applied to the 20 shoe.

The distributor consists of a metallic cap 20 having a conical portion terminating in an end portion of slightly enlarged diameter, this end portion being indicated by 21. The 25 diameter of the end portion 21 is such that it is slightly greater than the diameter of the opening 13 of the end of the container 10. Due to the resiliency of the metallic material and particularly of the flanges 12 thereof, this end portion 21 of larger diameter may be readily inserted into the opening 13 and by a snap action the enlarged portion 21 will seat itself within the container and within the flanges 12 and be held 30 in position thereby. The distributor cap has also a second enlarged portion, indicated by 23, which is adapted to seat upon the beveled end 11 of the container when the distributor 20 is placed in the position as 35 shown in Figure 3. The distributor cap 20 suitably holds a felt pad, or a felt-like material of substantially disc shape, forming a felt pad distributor, indicated by 24 and which material is suitably adapted to distribute the compact material on the shoe.

The recess of the cap 15 is not in alignment with the recess 18 of the compact stick as otherwise when the compact stick is worn or used up and the cap reaches the 50 position as shown in Figure 6, the cap 15 would fall out of the container 10. For this purpose, the depression 30 in the cap 15 is disposed slightly at one side of the recess 18. This disposition of the recess requires when the compact stick is inserted that the cap be inserted first with the depression 30 in registration with the impression 14 and then a quick and slight turning movement around a crosswise depression 31 in the stick is given 55 to the stick to bring about the registration of the impression 14 with the recess 18. By this arrangement of the recess when the distributing cap 15 reaches the position as shown in Figure 6, it will be securely held 60 in position so as to enable the projecting

portion of the compact stick to be used up. When it is desired to remove the distributing cap and replace it by a new compact stick, to which a similar and new cap is applied, the stick is given a slight rotary movement to bring the recess of the cap into registration with the impression 14 and thereby the stick can be readily removed.

The improved stick container and applicator can be used in different forms. If it 75 is desired, the distributing cap 20 may be taken in one hand and applied to the compact stick 17, as shown in Figure 2, and the material adhering to the portion 24 may then be transmitted to the shoe and the shoe 80 thereby cleaned. If, however, the user prefers to apply the compact directly to the shoe, which in most cases is the preferable form, then the user takes the container 10 in the hand and first applies a compact 17 85 to the shoe, suitably distributing the necessary material on the shoe and then turns the container 10 around into the position as shown in Figure 1 and by means of the portion 24 distributes the material over the 90 shoe.

The improved device may be readily shipped in the form as shown in Figure 3, in which the initial and unused stick 17 is moved so as to have the cap 15 rest upon the 95 flanges 12 and so as to have the distributor cap inserted in the manner as shown in Figure 3, with the ring projection 23 resting against the bevel 11.

Preferably the interior diameter of the 100 bevel 11 is substantially equal to the exterior diameter of the shoulder 25 so as to give a frictional hold when the distributor is inserted, as shown in Figure 3, and thereby hold the parts securely in position during the shipment of the parts. Then, as before stated, if it is desired to use it in the manner shown in Figure 1, the cap 20 is removed, the stick 17 is moved to the position as shown in Figure 5 and the cap 20 is then 110 inserted into the opening 13.

The compact stick may be made of such materials or formulae so as to adapt it to either buck, or canvas, or suède shoes or nappy leathers, and preferably has suitable 115 particles of a gritty substance that works down into the nap of the leather, cleaning the leather and at the same time carrying the color down to the body portion of the leather instead of merely smearing the surface. The felt pad buffer in the distributing cap is of such a character that it will readily rub the powder into the leather.

My improved device is of a very neat 125 character and may be ornamented by suitable advertising material thereon and being made in a relatively small size may be readily carried in a small hand-bag or pocket. The compact material of course 130 can be made in all shades of colors.

I have described my invention in the form of a particular embodiment but it is clear that changes may be made therein without departing from the spirit of the invention as defined in the appended claims.

I claim as new:

1. A shoe cleaning stick container, applicator and distributor, comprising a container having openings at both ends thereof, an inwardly extending annular flange on one end of the container, a compact stick adapted to move within the container and to be projected from the other end of the container, and a distributing cap adapted to close either end of the container and provided with a suitable material forming an applicator adapted to be in position for use when the cap closes that end of the container provided with the annular flange and to be closed within the container when the cap closes the other end of the container.

2. A shoe cleaning stick container and applicator comprising an open-ended cylindrical container, an inwardly extending flange formed on one end of the container, an interior projection formed on the container wall adjacent an end thereof, a compact stick slidable in said container, the compact stick having a groove cooperating with the projection to prevent rotation of the stick, a cap carried by the stick and hav-

ing a similar groove formed out of alignment with the groove on the stick, and an applicator member adapted to close either end of the container.

3. A shoe cleaning stick container and applicator comprising a container having one end thereof entirely open and the material of the container bent into the form of a bead, the other end of the container having an inwardly extending annular flange, a distributing cap having a bead of a diameter slightly greater than the diameter of the opening formed by the annular flange of the container, and having another bead of substantially the same diameter as the bead on the end of the container, said distributing cap being adapted to be inserted within the container at one end thereof when not in use, with its bead of the same diameter as the beaded end of the container engaged with the beaded end of the container and held in position by frictional engagement with the interior wall of the container, and being adapted to be removed therefrom and inserted in the other end of the container with annular flange of the container holding the smaller beaded portion of the cap.

In testimony that he claims the foregoing as his invention, he has signed his name hereto.

ANTHONY L. ASTE.
